UNITED STATES PATENT OFFICE.

HUGO E. ROSENKRANZ, OF OSHKOSH, WISCONSIN, ASSIGNOR TO OSHKOSH LOWERING DEVICE CO., OF OSHKOSH, WISCONSIN, A CORPORATION OF WISCONSIN.

GRINDING DEVICE.

Application filed February 21, 1920. Serial No. 360,354.

To all whom it may concern:

Be it known that I, HUGO E. ROSENKRANZ, a citizen of the United States, and resident of Oshkosh, in the county of Winnebago and State of Wisconsin, have invented new and useful Improvements in Grinding Devices, of which the following is a description, reference being had to the accompanying drawings, which are a part of this specification.

The present invention relates to certain new and useful improvements in grinding devices and refers more particularly to a device of this character especially adapted for use at soda fountains or the like places for comminuting nuts for use in connection with the special dishes dispensed at such fountains.

One object of the present invention is to provide a neat and compact grinding device having a removable container for the whole nuts and provided with means whereby the nuts may be ground when desired.

Another object of this invention is to provide a grinding device of the class described so constructed that the same may be readily taken apart for the purpose of cleaning to prevent the oil from the same from becoming rancid and spoiling the materials.

A further object of this invention is to provide improved cutting means whereby the positive feeding of the material within the container to the cutter is insured.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing I have illustrated one complete example of the physical embodiment of my invention constructed according to the best mode I have so far devised for the practical application of the principles thereof, and in which:

Figure 1 is a perspective view of my complete device illustrating the same as in operative position.

Figure 2 is a side view of my device, the material container being only partly shown and parts of the grinder proper being

broken away and in section to more clearly illustrate structural details, and

Figure 3 is a view part in section and part in elevation taken on the plane indicated by the line 3—3 of Figure 2.

Referring now more particularly to the accompanying drawing, my improved device consists of an upper section 5, and a lower section 6, the upper section 5 providing a feed hopper and having its upper end internally threaded as at 7 to receive the lower threaded end 8 of a globular container 9 preferably of glass.

The lower end of the section 5 is closed by two longitudinally extending walls 10 inclined downwardly toward each other and having their inner ends spaced a slight distance apart to provide an opening 11 communicating the section 5 with the section 6.

Suitable grinding means are positioned in the section 6 adjacent the opening 11 for comminuting the material within the section 5 as the same is fed through the opening 11.

The grinding means consist of two complementary cutting members 12 secured to a shaft 13 journalled in the lower section 6 and extending across the section centrally of the opening 11. The cutting members 12 each have a plurality of spaced apart series 85 of cutting teeth 14 adapted to pass between spaced apart cutting teeth 15 carried by each wall 10 at its inner end adjacent the opening 11. The cutting or leading faces 14' of the teeth 14 are arranged on a plan 90 substantially parallel with an imaginary line drawn through the center of the cutter, and the space between the teeth of each series is sufficient to permit the material within the hopper section 5 and the container 9 to 95 be properly fed to the cutter.

As best shown in Figures 2 and 3, the cutting teeth of one cutter are staggered with relation to the cutting teeth of the other so that the material within the hopper 5 and the container 9 will be fed evenly therefrom and maintain the material within the container 9 substantially level. The cutters are secured to the shaft 12 by means of set screws or the like 16 and have a locking connection between each other by means of lugs 17 formed on one cutter and engaging in recesses 18 formed in the other cutter. The recesses 18 and lugs 17 are so positioned that the cutters may be arranged with their 110

teeth in the position depicted in Figures 2 and 3 or with the teeth of each cutter substantially in alignment.

The wall of the section 6 is inclined inwardly at its lower end as at 19 to provide a restricted discharge opening 20, through which the ground or comminuted nuts or other materials are discharged. The shaft 13, and with it the cutter 12, is rotated by means of a hand crank 21 secured to one end of the shaft which is projected beyond the lower section 6. The other end of the shaft 13 is secured in place by a screw or other fastening 22 whereby the same may be readily removed from the section.

As best shown in Figures 1 and 3, my grinding device is secured to a wall or other base (not shown) by means of a substantially V-shaped support 23 having its outer ends bent laterally to provide securing means 24 and having the apex of the V flattened as at 25 and secured to the section 6 by means of fastenings 26, see Figure 3.

As best shown in Figures 2 and 3, the section 5 has its lower portion reduced as at 27 and telescoped within the upper portion of section 6 and secured therein by means of suitable fastenings 28. This structure permits my device to be readily taken apart for the purpose of cleaning as will be readily apparent.

What I claim as my invention is:

1. A grinding device comprising a container, a partition therein including two opposed downwardly inclined walls projecting toward the center of the container and having their inner ends spaced to provide an opening, a series of spaced cutting teeth carried by the inner ends of the walls and formed with vertically extending cutting edges, and comminuting means positioned at

said opening comprising a shaft journalled in said container centrally of said opening, a plurality of annular members independently and circumferentially adjustably mounted on said shaft, teeth formed on said annular members and having radially extending cutting edges adapted to coact with said first mentioned teeth to form a shearing cut, and interlocking means between said members, whereby said members may be adjusted relatively to each other thereby aligning or staggering the respective teeth thereof as desired.

2. A grinding device comprising a hopper section the bottom of which is formed of two walls inclined downwardly towards its center and having their inner ends spaced to provide an opening, a lower section having its upper end secured to the bottom of the hopper section and its bottom provided with a restricted discharge opening, a series of spaced cutting teeth carried by the inner ends of said walls and formed with vertically extending cutting edges, a shaft journalled in said lower section longitudinally of the opening provided in the hopper section, a plurality of annular members independently and circumferentially adjustably mounted on said shaft, teeth formed on said members and having radially extending cutting edges adapted to coact with said first mentioned teeth to form a shearing cut, and interlocking means between said members, whereby said members may be adjusted relatively to each other thereby aligning or staggering the respective teeth thereof as desired.

In testimony whereof, I affix my signature.

HUGO E. ROSENKRANZ.
